ATTORNEY.

UNITED STATES PATENT OFFICE.

WADYH SIMON, OF NEW YORK, N. Y.

DESIGN FOR A PIPE.

SPECIFICATION forming part of **Design No. 25,546**, dated **May 26, 1896**.

Application filed December 30, 1895. Serial No. 573,831. Term of patent 31 years.

To all whom it may concern:

Be it known that I, WADYH SIMON, (having declared my intention of becoming a citizen of the United States, and having lived in the 5 United States for the last six years,) a resident of New York city, in the State of New York, have invented and produced a new and useful Design for a Pipe, of which the following is a specification, reference being had to the accompanying drawing, forming a part thereof.

The figure is a side elevation of my design. The leading features thereof consist in the unitary design, as shown, which represents a pipe provided with a stem in the shape of a 15 gun barrel and stock, with a snake entwined about the same and holding the pipe-bowl in its mouth. The coil of the snake begins near

the mouthpiece of the pipe and extends to the butt of the gun, where the bowl is held in its mouth, as shown.

a represents the gun, and *b* the snake, and the whole forms a design for a symmetrical, unique, and complete article of manufacture.

I claim—

The design for a smoker's pipe as herein described and shown.

In testimony that I claim the foregoing as my invention I have signed my name, in presence of two witnesses, this 28th day of August, 1895.

WADYH SIMON.

Witnesses:

GEORGE F. BUTLER,
THOS. A. BRADLEY.
